RESILIENT SEAT

Application filed August 8, 1928. Serial No. 298,164.

This invention relates generally to resilient seats and more specifically to an improved resilient seat or stool designed and intended particularly for use by engineers and firemen in cabs of railroad locomotives.

Prior to this invention engineers and firemen of railroad trains, while on duty in the cabs of the locomotives of the trains were compelled to use seats which were non-yieldably fixed to walls of said cabs. The result of this condition was that engineers and firemen frequently complained that the rough riding characteristics of the locomotives subjected them to very great discomfort and interfered with efficient performance of their duties.

To remedy the situation referred to, we have devised the resilient seat or stool disclosed herein which, because of its use and surroundings is heavily constructed, preferably of metal, and comprises, briefly stated, a fixed frame which rests upon the floor of the cab, and a movable seat supporting frame yieldably connected to said fixed frame by means of coil springs or other suitable yieldable means. The movable frame referred to is suitably guided by portions of said fixed frame and said movable frame is provided with a foot rest which moves therewith.

When seats or stools constructed in accordance with our invention are employed in the cabs of locomotives, it has been found that the engineers and firemen are made much more comfortable while at work, hence they are able to perform their duties in a much more efficient manner than when the rigid seats formerly employed were used by them.

Fig. 1 is a front elevation of a resilient stool constructed in accordance with our invention.

Fig. 2 is a side elevation of the stool shown in Fig. 1.

Fig. 3 is a cross section on line 3—3 of Fig. 1 looking downwardly.

Fig. 4 is an enlarged fragmentary cross section taken on line 4—4 of Fig. 2.

In the drawing wherein is illustrated one embodiment merely of our invention, A designates our improved resilient stool generally, said resilient stool comprising a fixed

frame 1 and a movable frame 2 supported for vertical movement by said fixed frame 1. Mounted at the upper portion of the movable frame 2 is a seat 3 which is preferably, though not necessarily, upholstered or cushioned to render same comfortable to the user of the stool.

The fixed frame 1 rests upon the floor of the locomotive cab or other compartment wherein the improved stool is used and so that same may have the required stability to withstand swaying of the locomotive cab when the stool is used for that purpose, we provide the side rails 4 at the bottom of the fixed frame 1 with inwardly projected and horizontally disposed flanges 5 which contact with the floor. The fixed frame 1, which is preferably rectangular in cross-section, includes a plurality of vertically disposed corner members 6, said corner members being preferably formed integral with the side rails 4 at the bottom of said fixed frame.

Extended forwardly from the oppositely disposed vertical members 6 of the fixed frame 1 is a pair of extensions 7, said extensions 7 being provided with inwardly projected and horizontally disposed flanges 8 (Fig. 1). Fixed to the flanges 8 of the extensions 7 by means of bolts or other suitable fastening devices 9 is a cross bar 10. The cross bar 10 is extended transversely of the fixed frame 1 at the front thereof and serves to secure together the vertical members 6 of said fixed frame. Extended rearwardly from the oppositely disposed vertical members 6 at the rear of the fixed frame 1 is a pair of extensions 11 resembling the extensions 7 already referred to, said extensions 11 being provided with inwardly extended and horizontally disposed flanges 12 to which a cross bar 13 is secured by bolts or other fastening devices. The cross bar 13 extends transversely of the fixed frame 1 at the rear thereof and said bar 13 serves to secure the oppositely disposed vertical members 6 at the rear of the fixed frame together.

At the bottom of the fixed frame the side rails 4 are tied together by bars 14 which are secured at their opposite ends by means of bolts, for in-

stance, to said side rails and extend transversely of said fixed frame.

Referring now to the movable frame 2, said frame includes a plurality of corner members 15 which extend downwardly from the seat 3. From the lower edge of the seat 3 to the points 15' spaced downwardly from said lower edge of the seat (Fig. 2) the downwardly extended members 15 of the movable frame are L-shaped in cross section as shown clearly in Fig. 3. These L-shaped portions of said members 15 embrace the upper portions of the vertical members 6 of the fixed frame, that is to say the inner angular faces 15 of said L-shaped portions contact with side and edge faces of said members 6 so that while the movable frame 2 is freely movable in a vertical direction with respect to the members 6 of the fixed frame, said movable frame 20 may not move horizontally with respect to said members 6 of said fixed frame, hence the movable frame is positively guided by the members 6 of the fixed frame. At the lower portions of the members 15 of the movable frame 25 said members are provided with channel portions 16, which latter portions embrace the vertical members 6 of the fixed frame at the lower portions thereof. The inner faces of the channel portions 16 referred to contact with the inner faces and edge faces of the vertical members 6 of the fixed frame hence said channel portions serve to aid in permitting vertical movement of the movable frame 2 while said channel portions 30 assist in preventing horizontal movements of said frame. The members 15 of the movable frame are tied together to add rigidity to the frame structure by means of a plurality of bars 17 and a plurality of bars 18 extended 35 transversely of the movable frame at the upper and lower portions respectively thereof.

Arranged at the front of the stool A is a plurality of expandable coil springs 19, the upper end of each of said coil springs being 40 attached to an eye forming a portion of a bolt 20, secured to the bar 10 at the front of the fixed frame 1 and the lower portion of each of said coil springs being attached to a similar bolt secured to the particular bar of the plurality of bars 18 which is located at the front of the movable frame. The bar 18 to which the lower ends of the coil springs 19 are attached is located in approximate vertical alignment with the bar 10. At the rear of the 45 stool we provide a second plurality of coil springs 21, each coil spring of the last mentioned plurality of coil springs being attached at its upper end to the eye portion of a bolt secured to the bar 13 at the rear of the fixed 50 frame of the stool and the lower end of each of said coil springs being attached by means of a bolt having an eye portion, to the particular bar of the plurality of bars 18 which is located at the rear of the movable frame 55 of the stool.

Secured by means of bolts or other suitable fastening devices to the vertical members 15 of the movable frame 2 which are located at the front of the stool is a pair of oppositely disposed L-shaped brackets 22. The vertically extended legs of the L-shaped brackets are each provided with a plurality of apertures 23 as shown clearly in Figs 1 and 2.

24 designates a foot rest which is pivotally attached to the oppositely disposed L-shaped brackets 23 by means of a shaft 25, said foot rest at its opposite ends being provided with L-shaped elements 26 which are secured by means of bolts 27 to said foot rest. The shaft 25 referred to is supported in a horizontally aligned pair of the apertures 23 formed in the oppositely disposed L-shaped members 22 and said shaft passes through apertures formed through the L-shaped elements 26 at the rear portions thereof so as to pivotally support said foot rest, and said L-shaped elements 26 are each provided with a stop member 28 formed thereon adapted to contact with the adjacent L-shaped bracket 23 whereby said foot rest may be maintained in a horizontal position.

In the use of an improved resilient stool it is plain that shocks resulting from uneven riding of the locomotive in the cab of which the stool is used will be absorbed by the coil springs 19 and 21, the movable frame of the stool, together with the seat 3, and foot rest 24, moving with respect to the fixed frame of the stool. It is also obvious because of the construction of the stool that the stability thereof will be maintained at all times when same is in use in the cab of a locomotive, and that its durable structure will withstand the rough usage to which it will be subjected.

If desired, we may provide our improved resilient stool with a removable back rest 30 and to the end that same may be readily detached from the stool we attach a pair of supporting devices 31 to the vertically disposed members 15 of the movable frame of the stool, said supporting devices being each provided with a vertically extended portion 32. Fixed to the back rest 30 is a pair of members 33, each of which is provided with a lower portion provided with a recess or socket 34. To attach the back rest 30 to the stool, said back rest is moved to a position where the vertically extended portions 32 are extended into the recesses or sockets 34 at the lower ends of the members 33 secured to said back rest whereby said back rest will be maintained in the position in which same is shown in Figs. 1 and 2.

We claim:

1. A resilient stool comprising a fixed frame including a plurality of vertically disposed frame elements arranged at the corners of said fixed frame, a movable seat supporting frame having downwardly extended portions guided by said vertically disposed

frame elements of said fixed frame, a seat at the upper portion of said seat supporting frame and completely movable therewith, and yieldable elements comprising suspension springs located entirely beneath said seat for connecting said movable frame to said fixed frame.

5 2. A resilient stool comprising a fixed frame including a plurality of vertically disposed frame elements arranged at the corners of said fixed frame, a movable seat supporting frame having downwardly extended angular portions which embrace and are guided by said vertically disposed frame elements of said fixed frame, a seat at the upper portion of said seat supporting frame and completely movable therewith, and yieldable elements comprising suspension springs located entirely beneath said seat for connecting said movable frame to said fixed frame.

10 20 3. A resilient stool comprising a fixed frame including a plurality of vertically disposed frame elements arranged at the corners of said fixed frame, a movable seat supporting frame having downwardly extended L-shaped portions which embrace and are guided by said vertically disposed frame elements of said fixed frame, a seat at the upper portion of said seat supporting frame and completely movable therewith, and yieldable elements comprising suspension springs located entirely beneath said seat for connecting said movable frame to said fixed frame.

15 25 30 35 In testimony whereof we have hereunto set our hands.

CHARLES E. HORSLEY.
THOMAS A. SAILOR.
